George H. Chapman,
By Samuel N. Pond,
Atty.

UNITED STATES PATENT OFFICE.

GEORGE H. CHAPMAN, OF CHICAGO, ILLINOIS.

STOP-ACTUATING DEVICE FOR PIPE ORGANS, ETC.

Application filed May 5, 1921. Serial No. 466,884.

To all whom it may concern:

Be it known that I, GEORGE H. CHAPMAN, a citizen of the United States, residing at Chicago, in the county of Cook and State of Illinois, have invented certain new and useful Improvements in Stop-Actuating Devices for Pipe Organs, Etc., of which the following is a specification.

This invention relates to stop actuating mechanisms for pipe organs and other musical instruments of that type wherein the stops are electrically actuated and are controlled by individual circuit closers connected to and manually operated by either draw stops, stop-keys or pivoted tablets, and also actuated, in predetermined combinations, by power devices. Heretofore pneumatics have almost universally been employed for actuating the circuit closers in combinations, and one object of my invention is to provide a practical and simple electrical circuit opening and closing means in lieu of the pneumatic means heretofore used. Where the manually operated circuit controllers are actuated in circuit closing direction by pivoted stop-keys, it has been customary to mount the latter side by side in rear of a wooden bar or strip, the latter being slotted to allow the stop-keys to project therethrough, and the latter are held in "on" and "off" positions by springs, the upper ends of which bear against regulating screws entered into the rear side of the bar or strip, above the slot. It has been found in practice that where a long row of stop-keys is thus mounted, the combined efforts of all the stop-key controlling springs, will, in time, spring or bow the wooden bar or strip and thus throw the abutment points of the springs out of correct relation to their bearing points on the stop-keys and the fulcrums of the latter so that a stop-key, when thrown on or off, will not have a tendency to stay in set position. Another object of the invention is to provide a construction which will entirely remedy the fault above noted. Again, in the few cases where magnets were used as a direct means of operating the stop-key levers in place of the pneumatic above referred to, the magnets were mounted on a wooden base board behind the front strip or bar, in or through which, the

stop-key levers are mounted. As these magnets were of the pivoted-armature type, they required very delicate and accurate regulation in order to operate on the low voltage which is specified for musical instruments. Therefore, any swelling or shrinking of the wood, due to climatic and temperature changes, altered the distance sufficiently to throw the operating magnet out of regulation with the stop-key lever to which it is connected. This prevented the correct actuation of the stop-key and consequently of the circuit closers.

Another object of the invention is to provide a construction by which the length of the connection between the stop-key and the movable power actuated circuit closing member is always maintained uniform and constant, thereby obviating the fault last above noted. Still other objects and advantages of the invention will be apparent to those skilled in the art as the same becomes better understood by reference to the following description, taken in connection with the accompanying drawings, in which I have illustrated a practical and approved embodiment of the invention and wherein:

Fig. 1 is a top plan view, showing a single stop key and electro-magnetically actuated circuit closer associated therewith;

Fig. 2 is a vertical section on the line 2—2 of Fig. 1;

Fig. 3 is a diagram, showing the tandem windings of a solenoid magnet;

Fig. 4 is a detail view in horizontal section on the line 4—4 of Fig. 2; and

Fig. 5 is a perspective elevation of a bracket that is attached to the rear side of the front bar or strip.

Fig. 6 shows a modified form of bracket.

Referring to the drawings, 5 designates a base board, on the front of which is mounted a vertical strip or bar 6, the lower portion of which is formed with a longitudinal slot 7, on the top wall of which slot is the usual felt buffer strip 8. On the upper side of the base board 5, just in front of the bar or strip 6, is a ledge or shoulder 9 on which rests the usual felt buffer strip 10. To the rear wall of the bar or strip 6 are secured, side by side in juxtaposition, a series of metal brackets or units conveniently formed

as die castings and best shown in detail in Fig. 5. Each of these brackets comprises an upper attachment plate 11, a pair of parallel tapered side walls 12 forming trusses, and a horizontal base plate 13, which latter preferably rests upon a narrow wooden ledge 14 formed on or attached to the base board 5. The attachment plate 11 is apertured to receive a fastening screw 15 that enters the bar or strip 6, as clearly shown in Fig. 2; and directly above the screw 15 is a tapped boss 16 which receives the regulating screw 17.

The side walls 12 are formed with registering apertures 18 a slight distance above their lower ends, in which apertures is mounted a pivot or fulcrum rod 19.

On the free edge of the base plate 13 of the bracket is an apertured lug 20 for a purpose hereinafter described. As shown in Fig. 1, the face of the attachment plate 11 which lies in contact with the bar or strip 6 is preferably formed slightly concave, as indicated at 11'. The purpose of this is two-fold. In the first place, it well adapts the bracket to set firmly onto either a curved or straight bar or strip; also the edges only come in contact with the wood, and when screwed home, bite into the latter and thus increase the rigidity of the mounting, requiring only one mounting screw.

Pivoted on the fulcrum rod 19 between the side walls of each bracket, is the stop-key 21 of the customary form, the inner end 35 of the stop-key being slotted and having secured therein a brass plate 22 formed with a notch 23 in its upper edge. Between the notch 23 and the head of the regulating screw 17, is interposed the usual bow spring 24. The bearing point 23 of the lower end of the spring is so related to the fulcrum 19 of the stop-key and the abutment point of the upper end of the spring, that when the stop-key is in the "on" position shown by 40 full lines in Fig. 2, the point 23 lies forwardly of a straight line connecting the fulcrum 19 and the upper bearing point of the spring, and when the stop-key is in the "off" position shown by dotted lines in Fig. 45 2, the point 23 is shifted to the opposite sides of said line. With the three points thus related, the spring acts to snap and hold the stop-key in both "on" and "off" position. A nice and permanent adjustment 50 can be secured by adjusting the screw 17 inwardly or outwardly to shift the upper bearing point of the spring.

25 designates a wide, generally U-shaped metal frame, one limb 25' of which is herein shown as made separable and attached thereto by screws 26 for convenience in assembling the parts carried within said frame. The limb 25' is attached at its lower end by a screw 27 to an angle bracket 28 mounted on the base board 5, while the

other limb of the frame has an integral horizontal extension 29 that is secured by a screw 30 to the boss 20 of the stop-key supporting bracket. Within the metal frame members 25 and 25' are mounted a pair of 70 solenoid coils 31 and 32 arranged tandem and having a single movable core or plunger 33 through both. One end of the plunger 33 is tapped to receive the threaded stem 34 of a coupling sleeve 34, in which latter is 75 swiveled by a ball and socket joint, one end of a bent connecting-rod 35. The other end of the connecting-rod 35 is bent at a right angle as shown at 35' (Fig. 1) and engaged with an aperture in the metal strip or plate 80 22 carried by the inner end of the stop key. The coupling sleeve 34 is formed with a squared portion 34a by which it may be readily turned to effect a nice adjustment of the length of the connecting-rod. In the other end of the movable core or plunger 33, is fitted an insulated plug 36 that extends with clearance through an aperture in the frame member 25' and likewise through a registering aperture in a contact block 37 85 attached to the outer side of the frame piece 25' with an interposed paper or fiber insulation 38. In the outer end of the plug 36 is mounted a depending contact pin 39 that lies between a pair of spring contacts 40 mounted in or on the contact block 37 and, when moved inwardly, closes an organ stop or other circuit 41 through said contacts, and when moved outwardly breaks such circuit; the two positions of the pin 39 being 90 clearly indicated in Fig. 4.

The circuit closer can be operated by either one of two means: It can be manually operated by depressing the stop-key 21 to close the circuit, and raising the same to open the circuit. The circuit closer can also be operated by a power device. A predetermined combination of organ stops is obtained by throwing into, or out of use, several of the circuit closers simultaneously, each circuit closer then being operated by energizing one of the solenoid coils 31 or 32; the stop-keys being, of course, idly actuated during such magnetic actuation of the circuit opening and closing device.

Fig. 3 diagrammatically illustrates the windings of the tandem solenoid magnets. One end of each winding is shown as connected through a common lead 42 to a terminal post 43, and their other ends are connected by leads 44 and 45 to posts 46 and 47, respectively. For convenience the posts 43, 46 and 47 are herein shown as mounted in and projecting from the frame leg 25' with suitable insulation. The central post 43 is permanently wired to one side of a generator, and the posts 46 and 47 are wired to the opposite side of the generator with a suitable switch interposed for closing the circuit through one or the other of the posts 115 120 125 130

46 and 47 whereby to energize either winding at will, accordingly as the circuit is to be opened or closed. These last-mentioned details are not herein shown as they form no part of the present invention.

The practical utility and value of the described metal brackets will be readily understood from the foregoing, but may be briefly alluded to as follows: The upward and outward thrust of the battery of springs 24 is not directly taken by the comparatively light wooden bar or strip 6, but is resisted by the brackets which are mounted in close lateral contiguity, so that they cannot bend or bow the strip 6, and hence no accidental displacement of the abutment points of the springs 24 can occur, and no twisting strain on the bar 6 exists. The magnet supporting frame being directly connected to the lower end of the stop-key bracket, no accidental variations, from climatic and temperature changes, can occur that will alter the correct position of the plunger core in relation to the windings and circuit closer.

25 Finally, for the purpose of actuating stop combinations I have found that the tandem solenoid form herein shown and described is economical of space, simple in construction, noiseless in operation, economical in current consumption, and enables a much larger battery of stop actuating devices to be assembled in a given space than has heretofore been possible. It also permits of placing the stop-action contacts or circuit closers in a more accessible place than has heretofore been possible.

In Fig. 6 I show a slightly modified form of bracket the same including, in addition to the features already described, a pair of upper and lower lips 50 and 51 on the strip or bar engaging face of the bracket which lie in the slot of the strip or bar 6 and constitute stops for the stop-key, the latter having upper and lower buffer cushions 52 and 53 attached thereto.

The chief point in favor of a magnet over a pneumatic lies in its greater longevity and practical indestructibility. It cannot become leaky, and is not vulnerable to mice and other vermin.

Manifestly, the device may be considerably modified in respect of structural details without altering its substantial character or principle, or sacrificing any of the advantages inherent therein. Hence, I reserve all such variations and modifications as fall within the spirit and purview of the appended claims.

I claim:

60 1. In a stop actuating device for musical instruments, the combination of a solenoid magnet, a plug of insulating material attached to one end of the plunger of said magnet, a contact member carried by said plug, a manually operable stop-actuating

member, and a link connecting said stop-actuating member to the other end of said plunger.

2. In a stop actuating device for musical instruments, the combination of a pair of oppositely wound solenoid magnet coils disposed tandem and having a common movable armature extending therethrough, a circuit opening and closing member carried by one end of said armature, and a manually operable stop-actuating member connected to the other end of said armature.

3. In a stop actuating device for musical instruments, the combination of a wooden bar, a metal bracket attached to the rear side of said bar, a stop key fulcrumed in the lower portion of said bracket, a spring abutment member on the upper portion of said bracket, and a stop-key controlling spring between the inner end of said stop-key and said abutment member.

4. In a stop actuating device for musical instruments, the combination of a wooden bar, a metal bracket attached to the rear side of said bar and formed with a tapped boss on its upper portion, a regulating screw mounted in said boss, a stop-key fulcrumed in the lower portion of said bracket, and a stop-key controlling spring between the inner end of said stop-key and said regulating screw.

5. In a stop actuating device for musical instruments, the combination of a wooden bar, a metal bracket attached to the rear side of said bar and formed with a tapped boss on its upper portion and parallel vertical side walls constituting truss members, a regulating screw mounted in said boss, a pivot pin mounted in and between the lower portion of said side walls, a stop-key fulcrumed on said pivot pin, and a stop-key controlling spring between the inner end of said key and said regulating screw.

6. In a stop-actuating mechanism for musical instruments, the combination with a panel strip, of a metal bracket attached to the rear side of said panel strip and having a transversely concave wall lying against said panel strip, and a stop key pivotally mounted on said bracket.

7. In a stop actuating device for musical instruments, the combination with a base board, and a strip or bar above said base board, of a metal bracket mounted on the rear side of said strip, a pivoted stop-key and its controlling spring mounted on said bracket, a frame attached at one end to said base-board and at its other end to said bracket, a motor supported by said frame and having a movable element connected to said stop-key, and a circuit contact member carried by the movable element of said motor.

8. In a stop actuating device for musical instruments, the combination with a base

board, and a strip or bar above said base board, of a metal bracket mounted on the rear side of said strip, and formed with an attachment lug on its lower end, a pivoted stop-key and its controlling spring mounted on said bracket, a frame attached at one end to said base board and at its other end

to said attachment lug, a solenoid magnet mounted in said frame and having one end of its plunger connected to said stop-key, and a circuit contact member carried by, and insulated from, the other end of said plunger.

GEORGE H. CHAPMAN.
